UNITED STATES PATENT OFFICE.

CHARLES L. DAVIS AND ARTHUR G. WATTS, OF ROBINSON, ILLINOIS.

ARTIFICIAL LIMB.

1,174,127.

Specification of Letters Patent. Patented Mar. 7, 1916.

Application filed December 3, 1914. Serial No. 875,282.

To all whom it may concern:

Be it known that we, CHARLES L. DAVIS and ARTHUR G. WATTS, citizens of the United States, residing at Robinson, in the 5 county of Crawford and State of Illinois, have invented certain new and useful Improvements in Artificial Limbs; and we do declare the following to be a full, clear, and exact description of the invention, such as 10 will enable others skilled in the art to which it appertains to make and use the same.

Our invention relates to improvements in artificial limbs and has for its main object to improve upon the construction of devices 15 of this character to such an extent as to provide simple, strong and light weight limbs which will possess a number of advantageous features.

To the above end, a further object is to 20 provide novel means for attaching the artificial limb to the stump, this means including a cushioning device composed of a plurality of flat springs to which the stump socket is secured.

25 Yet another object is to provide a simple yet efficient form of bearing for hingedly connecting the various members of the limb and to provide means whereby one of these hinged connections may operate only in one 30 direction.

With the above and minor objects in view, the invention resides in certain novel features of construction and combination herein described and claimed, and shown in the 35 drawings wherein;

Figure 1 is a front elevation of an artificial leg constructed in accordance with our invention; Fig. 2 is a side elevation; Figs. 3 and 4 are vertical sections as seen on the 40 planes of the lines 3—3 of Fig. 2 and 4—4 of Fig. 1; Figs. 5 and 6 are horizontal sections taken along the planes of the lines 5—5 and 6—6 of Fig. 4; Fig. 7 is a top plan view of a socket member to be described; Fig. 8 is 45 a detail vertical section taken on the line 8—8 of Fig. 3.

In the accompanying drawings an artificial limb 1 is shown, said limb being provided with a foot 2 on its lower end, which 50 foot is hingedly connected to the lower end of said limb by an ankle joint 3 to be described. The limb 1 is formed of an upper hollow shaft 4, a lower shaft 5, hingedly connected by a knee joint 6 between the upper and lower shafts and attaching means 7. The shaft 5 is provided, on its upper

end, with a socket member 8 whose upper face is provided with a semi-globular recess 9 and with a pair of grooves 10 which project laterally outward from said recess and 60 which receive the opposite ends of a horizontal shaft 11 which passes through and projects beyond the opposite sides of a ball 12, which is carried by the lower end of the shaft 4, said ends of the shaft thereby constituting bearing pins or journals. It will 65 be seen, by reference to the drawings, that the ball 12 rests within the recess 9 and upon an annular horizontal series of anti-friction ball bearings 13. Secured by screws 70 14 or by other suitable fasteners to the member 8 is a cap 15, the latter having a semi-globular recess in its under side which 75 contacts with the recess 9 to provide a complete bearing for the ball 12, said lower side of the cap 15 being also provided with a pair of laterally extending grooves 16 which register with the grooves 10 to provide complete bearings for the ends of the shaft 11.

At suitable points (see Figs. 3 and 8) recesses 17 are provided in the cap 15, said recesses intersecting the grooves 16 and receiving ball carriers 18 which revolvably support a plurality of anti-friction balls 19, the latter bearing against the upper side of the 80 shaft 11 as shown. As the various parts of the device become worn it becomes expedient to provide means for adjusting the carriers 18 downwardly, a thumb screw 20 being 85 here shown as provided for this purpose. 90

A knee joint 6 constructed as above described, possesses a number of advantageous features and allows free movement of the knee joint. In order to allow such movement, however, one edge of the cap 15 must 95 be notched as seen at 21 for the reception of the shaft 4, the upper face of the socket member 8 being preferably provided with a groove 22 which registers with the slot or notch 21 as clearly shown in the various 100 figures of the drawings. It will be readily understood, that the shaft 11 prevents the knee joint from operating in one direction, but allows perfect operation thereof in a plane at right angles thereto. 105

In connection with the parts above described, it becomes highly essential to provide means for preventing the joint 6 from bending to allow the shaft 5 to move forwardly. For this purpose, the upper shaft 110 4 is provided with a collar 23 from which arms 24 project forwardly and rearwardly

to opposite sides of the hinge, while a similar collar 25 is mounted on the shaft 5 and provided with forwardly and rearwardly extending arms 26. Connecting the rearmost arms 24 and 26 is a strap 27 which prevents the movement above mentioned, while the forwardly projecting arms are connected one to the other by a suitable elastic element 28, thereby allowing the proper bending movement of the knee joint.

The ankle joint 3 which connects the foot 2 with the lower end of the shaft 5, is constructed in the same manner as the joint 6 above described, with the exception that the socket 9' is formed directly in the foot instead of in a specially constructed socket member, and the cap 15' is yieldably connected to said socket member, to allow the leg to tilt sidewise a trifle in respect to the foot. It may likewise be explained, that the front and rear edges of the cap 15' are notched as seen at 21' in order to allow the ankle or hinge joint 3 to move in the necessary directions, it being understood that said cap is provided for retaining the ball 12' and the shaft 11' in position within the 9' and grooves 10' similar to the grooves 10 with the exception that they increase in depth at their outer ends to allow the shaft 11' to move vertically as the leg tilts sideways as above suggested. For yieldably connecting the cap 15' to the foot, screws 100 are passed through slots therein and threaded into said foot, springs 101 being interposed between the heads of the screws and the cap.

In order that the foot may be normally moved to a neutral position, a collar 30 is mounted on the shaft 5 directly above the joint 3, said collar being provided with forwardly and rearwardly extending arms 31 to which the upper ends of coiled springs 32 are secured, the lower ends of said springs being attached to the foot 2 in front and rear of the joint 3. By this construction, the proper movement of the ankle joint may take place.

Although the foot proper might be constructed in any suitable manner, it is preferably formed of a rear or body member and a toe member 33 which is spaced a slight distance therefrom and connected therewith by a flat leaf spring 34, the latter being secured to the under sides of the two members and being covered by a sponge rubber pad 35 as shown. By this construction, the toe member 33 may yield upwardly to the necessary amount, but is preferably limited in its downward movement by bolts 36.

60 The attaching means 7 comprises a nut 40 which is threaded upon the upper end of the shaft 4, a plurality of upwardly diverging flat leaf springs 41 whose lower ends are secured to said nut, their upper ends being formed in the loops 42, a strap

43 which encircles said upper ends of the springs and which passes through the loops thereon, and an adjustable socket 44 which is secured to the springs 41.

The socket 44 is of substantially cylindrical formation and is preferably constructed of sheet aluminum, the socket being slit on one side and having the edges, thus formed, overlapped as indicated at 45 in Fig. 2. At this point, a pair of ears 46 project outwardly from the meeting edges of the socket, said ears being perforated for the reception of a clamping bolt 47, having a thumb nut 48. By such construction, the nut 48 may be tightened and loosened to render the socket 44 applicable to stumps of different sizes.

As seen in the various figures of the drawings, the shafts 11 and 11' are reduced at their ends as shown at 50 and 50' respectively. The reduced ends of the shaft 11 are passed through the lower ends of a pair of upright side strips 51, and through the upper ends of lower side strips 52, the extreme lower ends of these last named strips being pivoted at 53 upon the reduced ends 50' of the shaft 11'. In making all of these pivotal connections, appropriate forms of ball bearings 54 are provided and nuts 55 are also employed for retaining the sections of the ball bearings in place and for preventing removal of the strips 51 and 52. The upper strips 51 are held in spaced relation by a pair of arms 60 which project laterally from a collar 61 mounted on the shaft 4, while the strips 52 may be so braced if desired.

Secured either to the inner or to the outer sides of the strips 51 and surrounding the upper shaft and the attaching member 7, is a covering 62 which is here shown as being formed of woven wire, while a similar covering 63 surrounds the lower shaft, and is secured to either the inner or the outer sides of the strips 52, said last named covering being extended downwardly and around the cap 15' as shown. By reference to the drawings it will be seen that both the thigh and calf coverings 62 and 63 are shaped to conform to the lines of the portions of the limb which they are replacing, thereby providing an extremely life-like appearance when the completed article is properly covered by the clothes of the wearer.

From the foregoing description taken in connection with the accompanying drawings, it will be seen that comparatively simple construction has been provided for carrying out the objects of the invention, yet that the efficiency of the device will not be impaired by such simplicity.

We claim:

1. An artificial limb comprising a pair of alined centrally disposed hingedly connect-

ed shafts, journals projecting laterally in opposite directions from the hinge thereof, attaching strips spaced laterally from the shafts and pivoted to said journals, and 5 light weight coverings surrounding said shafts and attached to said strips, said coverings being shaped to conform to the shape of the members which they replace.

2. An artificial limb comprising a pair of 10 members, a socket carried by one member, ball bearings in said socket, and a ball on the other member and seated within a socket on the ball bearings therein.

3. An artificial limb comprising a pair of 15 members, a socket carried by one member, ball bearings in said socket, a ball on the other member and seated within a socket on the ball bearings therein, and stop means for preventing relative movement of the two 20 members in one direction.

4. An artificial limb comprising a pair of members, a socket on one member, a ball on the other member and located in the socket, bearings on opposite sides of the socket and 25 journals projecting laterally from opposite sides of the ball and rotatably mounted in said bearings.

5. An artificial limb comprising a pair of 30 members, a socket on one member, a ball on the other member, and located in the socket, bearings on opposite sides of the socket, said bearings having recesses opening into their bores, ball carriers slidable in said recesses, anti-friction balls carried by said carriers, 35 means for moving the latter inwardly and outwardly, and transverse journals projecting laterally in opposite directions from said ball into said bearings and contacting with said anti-friction balls.

40 6. An artificial limb comprising a pair of members, a socket on one member, ball bearings in one side of said socket, a ball on the other member and mounted in the socket on the ball bearings therein, bearings on opposite sides of said socket, journals projecting laterally in opposite directions from said ball and extending into said bearings, and anti-friction balls in the latter and located adjacent the side of the socket opposite that 45 having the ball bearings.

7. An artificial limb comprising a pair of 50 members, a socket member on one of the same, said socket member having a semi-globular recess in one side and grooves extending laterally in opposite directions from said recess, a ball on the other member and located in said recess, a pair of journals projecting laterally from said ball into the grooves, and a cap secured to the socket 55 member and having a semi-globular recess co-acting with that therein to provide a bearing for the ball, said cap also having

grooves co-acting with those in the socket member to form bearings for the journals, and a slot through which the member having the ball projects. 65

8. In an artificial limb the combination with a pair of hingedly connected members, of a pair of arms projecting laterally from one member to opposite sides of the hinge, 70 similar arms on the other member, a strap connecting the arms projecting to one side of the hinge, and an elastic element connecting the arms projecting to the opposite side thereof. 75

9. The combination with an artificial limb, of a plurality of upwardly diverging springs secured to the limb, and a stump socket supported by said springs.

10. The combination with an artificial 80 limb, of a plurality of upwardly diverging leaf springs secured to the limb, and a strap passing around said springs.

11. The combination with a foot having a half bearing in its top, a cap above said foot 85 and having the second half of the bearing, and a leg rising from the foot and having a hinge member located in the bearing thus formed, of a yielding connection between the cap and foot. 90

12. The combination with a foot having a half bearing in its upper side, a cap above said foot and having the second half of said bearing, and a leg rising from the foot and having a bearing shaft mounted in the bearing thus formed, of a yielding connection 95 between the cap and the foot.

13. The combination with a foot having a semi-globular recess in its upper side, and a pair of grooves extending outwardly from 100 said recess in opposite directions, said grooves increasing in depth toward their outer ends, a cap above the foot and likewise having a semi-globular recess, whereby to provide a globular socket, a ball in said 105 socket, a leg member rising from said ball, a pair of journals projecting laterally from the ball into said grooves, and yielding means connecting the cap to the foot.

14. An artificial limb comprising a pair 110 of hingedly connected members, a pair of rigid arms extending from one member to opposite sides of the hinge, and a pair of coiled springs connected at one end to the arms and at their other end to the other 115 member on opposite sides of the hinge.

In testimony whereof we have hereunto set our hands in presence of two subscribing witnesses.

CHARLES L. DAVIS.
ARTHUR G. WATTS.
